FIG. 1.

FIG. 2.

INVENTOR

ETHEL L. ANDERSON

BY W. Teeue

ATTORNEY.

UNITED STATES PATENT OFFICE.

ETHEL L. ANDERSON, OF LOS ANGELES, CALIFORNIA.

DESIGN FOR A SWEATER-COAT.

51,831.

Specification for Design.

Patented Mar. 5, 1918.

Application filed October 30, 1917. Serial No. 199,364. Term of patent 3½ years.

To all whom it may concern:

Be it known that I, ETHEL L. ANDERSON, a citizen of the United States of America, residing at Los Angeles, in the county of Los Angeles and State of California, have invented a new, original, and ornamental Design for Sweater-Coats, of which the following is a specification, reference being had to the accompanying drawing, forming part thereof.

In the drawings, Figure 1 is a front elevation of the design, and Fig. 2 is a rear elevation of the coat.

What I claim is:

The ornamental design for a sweater coat, as shown.

Oct. 11, 1917.

ETHEL L. ANDERSON.
